(57) **CLAIM**

The ornamental design for an insert for toilet bag and toilet bag, as shown and described.

DESCRIPTION

FIG. 1 is a perspective view of a toilet bag;

FIG. 2 is a left side elevation view of the toilet bag illustrated in FIG. 1;

FIG. 3 is a right side elevation view of the toilet bag illustrated in FIG. 1;

FIG. 4 is a top plan view of the toilet bag illustrated in FIG. 1;

FIG. 5 is a bottom plan view of the toilet bag illustrated in FIG. 1;

FIG. 6 is a front elevation view of the toilet bag illustrated in FIG. 1;

FIG. 7 is a back elevation view of the toilet bag illustrated in FIG. 1;

FIG. 8 is perspective view of the toilet bag in an open position showing an insert for toilet bag contained in the toilet bag;

FIG. 9 is a perspective view of the toilet bag where the insert for toilet bag has been removed from the toilet bag; and,

FIG. 10 is a perspective view of the insert for toilet bag. In FIGS. 1-6 zippers and a strap for operating the zippers of the toilet bag are illustrated in broken lines that form no part of the claimed design.

In FIGS. 1-9 handles at the front and back end for carrying the toilet bag are illustrated in broken lines that form no part of the claimed design.

In FIG. 9 an attachment surface in an interior of the toilet bag is illustrated in broken lines that form no part of the claimed design.

1 Claim, 10 Drawing Sheets
